SUPPORT FOR NORMAL BODY LOCOMOTION

Byron M. Taylor, La Mesa, Calif.

Application April 26, 1940, Serial No. 331,765

8 Claims. (Cl. 128—80)

My invention relates to a support for normal body locomotion more particularly for use in connection with limbs of persons who have been disabled by disease such as infantile paralysis or other causes whereby support and guidance is given said limbs so that restoration of normal locomotion thereof is promoted.

From a physiological point of view every body movement of a person is the result of balanced contraction and inhibition of numerous opposed muscles or opposed groups of muscles as affected by their controlling nerves. The poise and readiness for instant action of any person's body depends upon the condition of the numerous balanced sets of opposing muscles and nerves in a person's body. This state of opposed muscle balance is known as muscle "tone" or "tonic contraction"; and in moving any part of the body, which is done by these opposed muscle groups, when one muscle or one set of muscles contracts, the tone of its antagonist is inhibited and the relative degree of contraction and inhibition depends upon the mass and speed of the organ in action. Thus in walking, the whole action of the leg and foot depends upon the relative degree of tone or elasticity of opposing muscles connected to the bones of the hip, leg and foot. Some of these opposing muscles are continuously taut like stretched rubber bands. In infantile paralysis, or like conditions, when one of these opposing muscle groups has been attacked leaving its opposing group unaffected, soon thereafter the affected muscle, because the disease prevents normal stimulation by the nerves, loses its elasticity and becomes flaccid. Then its antagonist having no opposition, sharply contracts, thereby overstretching the defective muscle and pulling their skeletal member, such as the foot, out of its normal position. Pathological literature stresses the fact that not until sometime later does atrophy of the affected muscle and other attendant evils begin. Because the affected muscle or muscles are abnormally stressed, the result is enfeebled circulation of the blood and constriction of the nerves. Because of these abnormal stresses thus set up, there is malnutrition of the bones. These abnormal stresses, plus immobility, over a period of time may cause ankylosis of the joints and deformities, such as clubfoot. Under conditions such as these, not only will the affected muscle atrophy, but its overly-contracted and disused antagonist will, after a time, also atrophy.

Modern treatment, to hold the affected organ in normal position begins by putting the affect-

ed organ in plaster casts and braces; but such casts do not permit any movement of either the unaffected or the affected muscles, and such immobility and disuse will of itself result in regressive metamorphosis and atrophy.

Accordingly it is proposed to provide a means of skeletal-muscular reinforcement in the form of an articulated brace means which may be applied to the patient at the end of the acute stage of the disease as soon as the affected group of muscles is discovered, which articulated brace means will not only support the affected body member, but which articulated brace means will also have yieldable tension members to substitute for the loss of elasticity of the affected muscle or group of muscles.

By providing such a means the over-extension of the affected muscle and the over-contraction of its antagonist will be prevented, normal circulation will be maintained, abnormal strains and stresses in muscles and deformities of bones will not occur; and because the limb will be held in a natural position, it may be exercised while the patient is convalescing; and with the patient kept in a normal position, all of his energy may be thus directed toward combatting the ravages of the disease itself.

Because of the muscle tone of a person, the skeletal and muscular system of each body member, as a leg or arm, is maintained in a state of dynamic equilibrium sometimes known in the science of anatomy and physics as "tone" or "resonance." By varying the tone or elasticity of the muscles, a "tuned" or "resonant" system is thus provided within the body for any particular function, such as walking or running, and this system accounts for the quickness and smoothness of bodily actions and for the tremendous amount of exercise the body can do by expending a comparatively small amount of energy. If a muscle or group of muscles loses its tone or elasticity, the tone of a body member actuated by those muscles is destroyed for all those actions which the affected member would normally perform, and its movement will then require excessive energy and will be awkward, jerky and spasmodic. In walking for example, under such conditions the entire complex system becomes unbalanced and distorted. In order to walk at all, the body is compelled by integrative adaptation, to ignore the affected factors and to alter the unaffected factors and thus evolve a new system of locomotion resulting in a perverted function of the body member.

It is proposed in addition to apply a means

of skeletal muscular reinforcement to the affected organ so that tonic unbalance will be prevented, to also provide for the adjustment or variation of the said means so that resonance of the entire system, natural and artificial, be gained thus enabling the person to maintain normal movement and positions of the affected limb, or member of the body.

At first an attendant will merely exercise the affected limb or member after the means of skeletal-muscular reinforcement has been adapted thereto. Because the tension of the yieldable means of the articulated brace means may be altered, the limb or member may be moved at different rates, and because the system is maintained at resonance, comparatively little energy will be required for movement, so that the patient will soon be able to aid in the exercise. During the later stages of convalescence, the affected limb, including its artificial counterpart, is kept and exercised in a state of resonance, so that the patient can re-educate himself in all the complicated reactions of self-locomotion.

With the above explanation in view the objects of my invention are:

First, to provide a support of this class which is arranged to compensate weakened muscles and provides a resonant balance for cooperating muscles in limbs of the disabled wearer and said support thereby providing a combined condition of resonance for the entire system, both natural and artificial, of normal locomotion.

Second, to provide a support of this class which is readily and easily fitted on and removed from the wearer's limbs;

Third, to provide a support of this class which is very light and comfortable to wear and therefore dissipates a very small amount of the wearer's energy;

Fourth, to provide a support of this class which guides and aids the action of weakened muscles in a disabled limb, thereby providing a restored dynamic balance of muscles in the limb which permits the graceful effortless movement as of a normal limb;

Fifth, to provide a support of this class which is arranged to compensate disabled and weakened muscles in both the upper and lower portions of the wearer's leg for restoring a resonant cooperative relation of the muscles of the entire limb;

Sixth, to provide a support of this class which is arranged to very closely duplicate the normal and natural action and function of the joints of the wearer's limb;

Seventh, to provide a support of this class wherein the knee joint member is arranged to retain a person's knee joint in secure and steady upright relation when in standing position and to simulate the natural path of the knee joint with its shifting axis;

Eighth, to provide a support of this class in which springs are arranged to control the inertia and opposing muscular tension of a person's disabled limbs so that tonic balance of the limb is maintained permitting the limb to develop normal muscles and a graceful action;

Ninth, to provide a support of this class which is readily adjustable and applicable to variously affected wearers;

Tenth, to provide a support of this class which affords and promotes normal action which is a necessity for normal growth and development and restoration of the function of normal muscles;

Eleventh, to provide a support of this class wherein the ankle joint member has substantially the same axes as the axes of the ankle joint itself, thus allowing for a freedom of movement approaching the normal; and

Twelfth, to provide a support of this class which is very simple and economical of construction, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of this application in which:

Figure 1 is a fragmentary side elevational view of my support for normal body locomotion; Fig. 2 is a fragmentary front elevational view thereof; Fig. 3 is a top or plan view showing the lower parts and portions omitted to facilitate the illustration; Fig. 4 is a fragmentary side elevational view showing the lower portion of my support for normal body locomotion from the opposite side, as shown in Fig. 1 of the drawing; Fig. 5 is a sectional view taken from the line 5-5 of Fig. 4; Fig. 6 is an enlarged fragmentary elevational view taken from the line 6-6 of Fig. 2; Fig. 7 is a similar view to Fig. 6 showing the opposite side of the mechanism as disclosed in Fig. 6; Fig. 8 is a similar view to Fig. 6 showing an edge elevational view of the mechanism thereof; Fig. 9 is a transverse sectional view taken from the line 9-9 of Fig. 6 and Fig. 10 is a transverse sectional view taken from the line 10-10 of Fig. 6.

Similar characters of reference refer to similar parts and portions throughout the several views of the drawing.

The limb brace members 1 and 2, knee joint member 3, ankle joint member 4, ankle joint member supports 5 and 6, shoe 7, limb supporting bands 8 and 9, hip joint member 10, hip engaging members 11 and 12, abdominal supports 13 and 14, sacrum engaging pad 15, and the compensation springs 16, 17, 18, 19, 20, 21 and 22 constitute the principal parts and portions of my support for normal body locomotion.

The limb brace member 1 is constructed of a tubular member 1a and a tube like member 1b which is telescopically positioned within the tube like member 1a, as shown best in Figs. 1 and 2 of the drawing. The lower end of this brace member 1 is pivotally supported on the ankle joint member 4 and is pivotally connected to the knee joint member 3 at its upper end by means of the pin 1c, as shown best in Fig. 7 of the drawing. Secured on opposite ends of this brace member 1 are substantially flat plate like members 1d in which are positioned pivotal bearings at the pivotal connection of the limb brace member 1 with the ankle joint member 4 and the knee joint member 3, all as shown best in Figs. 1 and 7 of the drawing.

The limb brace member 2 is of similar construction to the limb brace member 1 and is pivotally connected to the lower end of the hip joint member 10 at its upper end and is pivotally connected with the knee joint member 3 at its lower end by means of the pin 2a, as shown best in Figs. 1 and 7 of the drawing. Secured in the plate like portion 2b on the lower end of the brace member 2 is a pin 2c which is ar-

ranged to extend outwardly through the arcuate slotted portion $3a$ in the knee joint member 3 , all as shown best in Figs. 6 and 7 of the drawing. This pin $2c$ extends outwardly from the side of the knee joint member 3 and engages the lever $3b$, as shown best in Fig. 8 of the drawing. This lever $3b$ is pivotally mounted on the knee joint member 3 by means of a pin $3c$ and is provided with an angularly extending portion $3d$, which is arranged to engage a notched portion $3e$ in the sliding latch member $3f$ which is reciprocally mounted on the knee joint member 3 by means of a pin $3g$ secured to the knee joint member 3 and extending through the slotted portion $3h$ of said sliding latch member $3f$, all as shown best in Fig. 6 of the drawing. This sliding latch member $3f$ is provided with an angularly and inwardly extending portion $3j$ which is arranged to reciprocate in a slotted portion $3k$ in the knee joint member 3 as shown best in Fig. 9 of the drawing. The extended end $3m$ of the angular portion $3j$ is arranged to engage a notch portion $3n$ in the stop member $3p$, which is rigidly secured on the outer side of the plate like portion $1d$ secured on the upper end of the limb brace member 1 , as shown best in Fig. 6 of the drawing. The knee joint member 3 is provided with a downwardly extending portion $3r$ which is arranged to engage the stop member $3p$, as shown best in Figs. 6 and 10 of the drawing.

The ankle joint member 4 is pivotally mounted on the ankle joint member supports 5 and 6 at its opposite ends and is substantially of curved form as shown in Fig. 5 of the drawing, it being noted that the pivotal axis of this ankle joint member 4 is positioned diagonally in relation with the shoe 7 , as shown best in Fig. 5 of the drawing.

The ankle joint member supports 5 and 6 are secured in diagonal relation on the shoe 7 by means of screws $5a$ and $6a$, as shown best in Figs. 4 and 5 of the drawing.

The shoe 7 is substantially conventional in form and is arranged to support the ankle joint member supports 5 and 6 in rigid relation with each other so that the axes of the ankle joint member 4 is maintained in proper alignment with the wearer's ankle joint, it being noted that the axes of the ankle joint member 4 correspond to the main axes of the ankle joint itself of the wearer's limb. Thus a rolling and lateral movement is possible.

The limb supporting bands 8 and 9 are secured on the limb brace members 2 and 1 respectively adjacent the opposite ends of the knee joint member 3 , as shown best in Figs. 1 and 2 of the drawing. These limb supporting bands 8 and 9 are each provided with metallic band portions $8a$ and a suitable padding member $8b$ positioned internally of the metallic band portion $8a$, as shown best in Fig. 11 of the drawing. The opposite ends of the band portions $8a$ are adjustably secured together by means of a strap and buckle $8c$ and $8d$ respectively, all as shown best in Figs. 2 and 11 of the drawing.

The hip joint member 10 is substantially flat and strap like in form and is pivotally mounted on the hip engaging member 11 by means of a ball and socket joint $10a$ as shown best in Figs. 1 and 2 of the drawing. The opposite end of the hip joint member 10 is pivotally connected to the upper end of the limb brace member 2 .

Secured on the side of the hip engaging member 11 is a strap like member $10b$ which is arranged to partially surround the hip joint mem-

ber 10 , all as shown best in Figs. 1 and 3 of the drawing. The hip engaging member 11 is made of sheet metal and is shaped substantially as shown in Figs. 1, 2 and 3 of the drawing. This hip engaging member 11 is substantially U-shaped, as shown in Fig. 3 of the drawing and is arranged to support the hip engaging member 12 by means of the hinge $12a$ which is secured on the extending portion $11a$ of the hip engaging member 11 . These hip engaging members 11 and 12 are so arranged in their connection together that they conform with the hips of the wearer and are adjustably secured together at their ends by means of the straps $11b$. Secured on the extending portion $11c$ of the hip engaging member 11 is the abdominal support 13 . The abdominal support 14 is secured on the extending end $12b$ of the hip engaging member 12 , all as shown best in Figs. 2 and 3 of the drawing. These abdominal supports 13 and 14 are arranged to engage the abdomen of the wearer and provide relatively steady support of my support for normal body locomotion on the wearer.

Secured on the inner side of the hinge $12a$ is the sacrum engaging pad 15 . This sacrum engaging pad 15 cooperates with the abdomen engaging pads 13 and 14 in supporting my support for normal body locomotion on the wearer thereof.

The operation of my support for normal body locomotion is substantially as follows: Any person who has a disabled leg may place the shoe 7 on the foot of the disabled leg and fasten the limb supporting bands 8 and 9 above and below the knee respectively and the hip engaging members 11 and 12 are secured around the wearer's hips in substantially the relation to each other as shown in Fig. 3 of the drawing. The knee joint member 3 , together with its cooperating parts and portions, substantially duplicate the normal action of a person's knee.

The limb brace members 1 and 2 are pivotally mounted on the knee joint member 3 in opposed relation to each other and the axis of these limb brace members 1 and 2 are held in offset parallel relation to each other, as shown by dash line A in Fig. 7 of the drawing. Figs. 6 and 7 illustrate the standing position assumed by the knee joint member 3 when positioned on the wearer. The offset parallel relation of the limb brace members 1 and 2 provides an arrangement whereby the pivotal relation of the limb brace members 1 and 2 with the joint member 3 tends to hold the limb brace members 1 and 2 in rigid parallel upright relation to each other. In this standing position, as illustrated in Fig. 6 of the drawing, the extended portion $3m$ of the latch member $3f$ is positioned in the slotted portion $3n$ of the stop member $3p$, holding the joint member 3 in rigid relation with the limb brace member 1 . The pivotally mounted offset relation of the limb brace member 2 with the limb brace member 1 tends to force the pin $2c$ into engagement with the end portion $2d$ of the slotted portion $3a$ in the knee joint member 3 , all as shown best in Fig. 6 of the drawing. This connected relation of the limb brace members 1 and 2 provides a steady support whereby the standing position of a weakened limb is prevented from bending at the knee joint due to loss of muscular control thereof.

When the wearer of my support for normal body locomotion attempts to take a normal step and bends his knee slightly, the limb brace mem-

ber 2 pivots on the pin 2a in the knee joint member 3 and forces the pin 2c in the slot 3a into engagement with the upper end B of the lever 3b causing the portion 3d thereof to raise the latch member 3f disengaging the portion 3m thereof from a notched portion 3n in the stop member 3p permitting the limb brace member 1 to pivot on the pin 1c in the knee joint member 3. It will be noted that the pin 2c in the slotted portions 3a must pivot substantially twenty degrees on the pin 2a before the knee joint member 3 will be released from the rigid secured relation with the limb brace 1 and that as the wearer's knee returns to substantially the standing position, the compression spring C, in engagement with one side of the lever 3b, forces said lever 3b and the latch member 3f into engagement with the stop portion 3p thereby locking the knee joint 3 together with the limb brace 1. It will be noted that the downwardly extending portion 3r of the knee joint member 3 is arranged to engage one side of the stop portion 3p and prevent the further pivotal movement of the knee joint 3 relatively with the limb brace member 1, as shown best in Figs. 6 and 10 of the drawing. It will also be noted that the compensation springs 16 to 22 inclusive are secured intermediate various parts of my support for normal body locomotion in order to compensate for weakened muscles in various portions of the wearer's disabled limb. The springs 16 and 18 are secured on the hip engaging member 11 at their upper ends and are secured to the limb supporting band 8 at their lower ends. These springs 16 and 18 are arranged to compensate for weakened muscles in the upper portion of the leg and are arranged to control the inertia and jerky reaction of muscles in the upper leg. The spring 17 is secured at its upper end to the hip engaging member 11 and is secured to the limb supporting band 9 at its other end. This spring is arranged to compensate for weakened muscles in the back side of the upper leg. The spring 19 is interposed between an outwardly extending pin 2e on the limb brace member 2 and the limb brace member 1 near the lower end of the knee joint member 3, as shown best in Fig. 6 of the drawing. This spring 19 tends to hold the knee joint member 3 in substantially the position as shown in Fig. 6 of the drawing. This spring 19 is applied when the patient's knee has a tendency to bend due to loss of muscular control. This spring 19 operates as an inverse function spring tending to hold the knee in steady upright position when standing and operates inversely after the knee is bent substantially 20° so that aid is provided in the bending action of the knee. The springs 20 and 21 are arranged to compensate for weakened muscles in the lower leg which control the use of the ankle and foot. These springs 20 and 21 are interposed between the limb supporting band 9 and the ankle joint member 4 and supports 6, as shown best in Figs. 1 and 2 of the drawing. The spring 22 is interposed between the ankle joint member 4 and the ankle joint member brace 5 for compensation of muscles controlling the tiltable relation of the ankle from side to side. These compensation springs 16 to 22 inclusive are applied in substantially the positions as shown and described for treatment of various weakened muscles in the wearer's leg.

It will be noted, however, that certain springs may be omitted to suit the particular case to which my support for normal body locomotion is

applied, each weakened muscle being given aid by a spring secured on the support in substantially parallel relation and arrangement with the weakened muscle. Since the muscles in a person's limb are opposed and positioned in counter tension relations, the tonic balance becomes destroyed by disease or disablement of any of the opposed muscles. It is therefore desired to compensate for the weakened muscle or muscles by adding a spring or springs of substantially equivalent tension with the unbalanced relation between the two opposed muscles.

In this manner the tonic balance of the opposed muscles is restored providing a chance for the weakened muscle or muscles to exercise without undue strain and in normal movements, thus stimulating the nerves and circulatory systems toward their correct behavior pattern.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In a support for normal body locomotion of the class described, the combination of a pair of relatively and longitudinally shiftable limb braces and a knee joint member, said limb braces separately pivotally connected with said knee joint member in offset parallel relation to each other when in standing position, means for holding said limb braces in offset parallel relation, an ankle joint member pivotally connected to the lower end of one of said limb braces, and a shoe pivotally supported on said ankle joint member with its pivotal axis diagonally disposed to the axis of the pivotal connection between said limb brace and said ankle joint member.

2. In a support for normal body locomotion of the class described, the combination of a pair of relatively and longitudinally shiftable limb braces and a knee joint member, said limb braces separately pivotally connected with said knee joint member in offset parallel relation to each other when in standing position, means for holding said limb braces in offset parallel relation, an ankle joint member pivotally connected to the lower end of one of said limb braces, a shoe pivotally supported on said ankle joint member with its pivotal axis diagonally disposed to the axis of the pivotal connection between said limb and said ankle joint member, and a hip engaging member pivotally connected with the upper end of one of said limb braces.

3. In a support for normal body locomotion of the class described, the combination of pivotally connected limb brace members, limb supporting bands secured thereon at opposite sides of the pivotal connection of said limb brace members and compensation springs cooperatively connected with said limb brace members and said limb supporting bands, an ankle joint member pivotally connected to one of said limb brace members, and a shoe pivotally supported on said ankle joint member with its pivotal axis diagonally disposed to the pivotal connection between said limb brace member and said ankle joint member.

4. In a support for normal body locomotion of the class described, the combination of pivotally

connected limb brace members, limb supporting bands secured thereon at opposite sides of the pivotal connection of said limb brace members and compensation springs cooperatively connected with said limb brace members and said limb supporting bands, an ankle joint member pivotally connected to one of said limb brace members, a shoe pivotally supported on said ankle joint member with its pivotal axis diagonally disposed to the pivotal connection between said limb brace member and said ankle joint member, and compensation springs interconnecting said ankle joint member and one of said limb supporting bands.

5. In a support for normal body locomotion of the class described, the combination of a limb brace member, an ankle joint member pivotally connected to the lower end of said limb brace member, a shoe pivotally supported on said ankle joint member with its pivotal axis diagonally disposed to the axis of the pivotal connection between said limb brace member and said ankle joint member.

6. In a support for normal body locomotion of the class described, the combination of a pair of limb braces and a knee joint member, said limb braces connected with said knee joint member,

pin and slot means controlling the relative movement of said limb braces and an inverse function spring interconnecting said limb braces at opposite ends of said knee joint member.

5. 7. In a support for normal body locomotion of the class described, the combination of a pair of limb braces and a knee joint member, said limb braces connected with said knee joint member, a pin secured to one of said limb brace members and said knee joint member provided with a slot in which said pin is reciprocally mounted and an inverse function spring interconnecting said limb braces extending substantially parallel with said limb braces over said knee joint member.

8. In a support for normal body locomotion of the class described, the combination of a pair of limb braces and a knee joint member, said limb braces connected with said knee joint member in pivotal relation with each other and an inverse function spring connected with said limb braces in substantial alignment with said braces and said knee joint member arranged to pass over the pivotal joint of said knee joint member with said limb braces.

BYRON M. TAYLOR.
